RIGHT-OF-WAY SIGNAL LAMP FOR VEHICLES

Joseph René Ayotte, Chicago, Ill.

Application April 26, 1955, Serial No. 35,693

Term of patent 14 years

(Cl. D72—1)

Fig. 1.

Fig. 2.

Fig. 3.

Fig. 1 is a front elevational view of a right-of-way signal lamp for vehicles, showing my new design;

Fig. 2 is a front elevational view thereof to a smaller scale illustrating its application to the body of a vehicle; and

Fig. 3 is a top plan view of the lamp.

The dotted lines shown in the drawing are for illustrative purposes only.

I claim:

The ornamental design for a right-of-way signal lamp for vehicles, as shown and described.
